UNITED STATES PATENT OFFICE

FRANCIS J. FOLEY, OF NORWOOD, MASSACHUSETTS

DEMONSTRATING DEVICE

Application filed December 28, 1929. Serial No. 417,127.

It has sometimes been attempted to show to a prospective purchaser of goods made in part at least of a sheet material such as paper, leather or fabric, or where sheet material is to be used associated with other objects, the appearance which may be expected in the completed article or assemblage by associating a sample of the sheet material with a miniature representation of the other parts 10 of the article, or of associated articles. Thus, for example, a cardboard cutout representing in miniature the contour of a garment has been laid over a fabric to show the fabric in the shape of the finished garment through the cutout, or a wall paper sample has been 15 associated with a miniature representation of a room which is to be papered. When the fabric has a distinctive pattern, however, this method of demonstration is unsatisfactory because the pattern is disproportionately large with respect to the article parts or articles represented in miniature, so that the impression due to this association is misleading and may be worse than useless.

In accordance with the present invention, therefore, the sheet material, instead of being associated for comparison with a representation in miniature of its immediate surroundings in a complete organization of one 20 or a plurality of associated articles, is associated with a fragmentary representation or representations of parts having certain important characteristic dimensions of full size. Thus the pattern of the fabric is made 25 to show up in proper relation to the full dimensioned neighboring parts so that the fabric is demonstrated in correct relationship thereto. By employing only fragmentary 30 representation of these adjacent parts, however, the size of the device necessary to enable the prospective purchaser to obtain the correct idea of the appearance of the finished article or association is held within the desired small limits.

For a more complete understanding of this invention, reference may be had to the accompanying drawings in which

Figure 1 shows in perspective a device embodying this invention for demonstrating va-

rious fabric upholstery coverings such as cretonne in connection with wicker furniture.

Figure 2 is an edge elevation of the same.

Figure 3 is a plan showing the device in use.

Referring to the drawings, at 1 and 2 are indicated sticks of material of different sizes and construction simulating in appearance and having the same cross sectional shapes and dimensions as certain frame members of an article of wicker furniture. These pieces 60 1 and 2 are preferably made of the same material as such frames, and any desired number may be used. They are shown as joined together at intervals by wrappings 3 of cane or cane-simulating material similar to that employed in wrapping frame members in wicker furniture, it being common to employ a plurality of pieces of such reed material arranged side by side and bound together by 65 cane wrappings. In order to simulate in these pieces a considerable number of different finishes for cane furniture frame members, these sticks may be colored differently between adjacent wrappings if desired. Likewise, 70 also the cane wrappings 3 may be differently colored to represent substantially full size different colored wrappings employed in the actual furniture. Closely associated with these pieces 1 and 2 are samples 75 of upholstery covering material, such, for example, as figured cretonne. As shown, these samples are fastened together at their upper ends as at 5 in Figure 3, the samples or swatches being arranged in the form of a 80 book or bundle which is secured to the sticks 1 and 2 as by the tying cords 6. These cords may pass through one of the sticks 1 or 2 through suitable holes 7 therein and these holes may also be availed of for the attachment of cords 8 by which the device may be 85 fixed to any suitable support, as for example, to the back of a piece of furniture with which the device is intended to be used. The samples are thus fixed to the sticks so as to leave 90 substantial portions of the sticks and wrappings exposed, and the various samples have free edge portions which can be brought up into juxtaposition with any selected portion 95 of either of the sticks 1 and 2 exposed between 100

the wrapping and likewise with the exposed portions of any selected wrapping.

As shown in Figure 3 any selected sample together with those behind it in the swatch 5 may be folded backwardly so as to bring an edge of the desired sample, with its forward face exposed, in juxtaposition to the sticks. Or by rolling or folding up those in front, the desired sample may be folded up to bring its 10 folded edge on its forward face into juxtaposition to the sticks. In this manner samples of cretonne which show the figures only on one face may be brought into juxtaposition to the sticks with their printed faces exposed. 15 Thus the upholstery material may be associated with a frame simulating element or a wrapping element of the color which is proposed for the corresponding part of a piece of reed furniture so that a correct determination 20 of the appearance of the particular sample of fabric, should this be used in upholstering an article of furniture may be clearly seen in its relation to the frame or wrapping portions of this piece of furniture. 25 Since the sticks 1 and 2 have certain characteristic dimensions, these being the cross sectional dimensions, the same as, or substantially the same as, those of the actual furniture, the pattern and colorings of the fabric material 30 present the same appearance with relation to the frame part that they would actually in a completed article of furniture upholstered with fabric identical with that of the sample being tested. By having the different 35 lengthwise portions of the stick elements between the wrapping colored and/or finished differently from each other, and which colors and finishes may be applied as desired to the corresponding parts of the actual article, the device is capable of being used to demonstrate a wide range of frame colors and finishes with a range of upholstery materials dependent on the number of samples or swatches in the device. 40

45 One embodiment of this invention having thus been shown and described, it should be evident to those skilled in the art that various changes and modifications might be made therein without departing from the spirit or 50 scope of the invention as defined by the appended claims.

I claim:

1. A device of the class described comprising a plurality of samples of sheet material 55 certain of which are figured, and a frame element to which said samples are attached, said element simulating a portion of a frame part adjacent to sheet material like any one of said samples in a complete organization of 60 which said sheet material is intended to form a part, that portion of said element corresponding to the normally exposed portion of said part being free to have associated therewith in the same relationship as in said organization any selected one of said samples, 65

said element having certain characteristic dimensions substantially the same as the corresponding dimensions of said part.

2. A device of the class described comprising a plurality of samples of upholstering sheet material, a member simulating a portion of a furniture frame element and of similar cross section, and means for attaching said samples to said member with the part corresponding to that appearing in the completed article of furniture exposed and with a portion of each sample free to be brought selectively into relation with the portion of said member comparable to that between said upholstering material and said frame element in the corresponding piece of furniture. 70

3. A device of the class described comprising a stick member simulating in appearance and of substantially the same cross section as a frame element of a piece of reed furniture, cane wrapping at one portion of said member simulating in appearance the cane wrapping of frame elements of such furniture, a plurality of samples of sheet upholstering material for use with such furniture fixed to 75 said stick leaving a substantial portion of said stick and wrapping exposed, each of said samples having a portion free to be brought into juxtaposition to said exposed portions of said stick and wrapping in relation similar 80 to the upholstery fabric frame member and cane wrapping of the article of furniture. 85

4. A device of the class described comprising a plurality of members each simulating and having substantially the cross section of frame elements of an article of wicker furniture, cane wrappings about said members simulating the wrapping of frame elements of said article, said members between said wrappings and the said wrappings being 100 colored to correspond with the colors applied to the corresponding elements of said article, a plurality of samples of sheet upholstery material, and means for fixing said samples to said members with substantial portions of said members and wrappings exposed, each of said samples having a portion free to be brought into juxtaposition to the exposed portions of any of the various colored portions 105 of any of said members and said wrappings comparable to the relation between said elements and wrappings of the upholstering material of the article of furniture. 110

In testimony whereof I have affixed my signature.

FRANCIS J. FOLEY.
